UNITED STATES PATENT OFFICE.

LEO EHRLICH, OF ST. LOUIS, MISSOURI, ASSIGNOR TO THE AMERICAN ROLL PAPER COMPANY, OF SAME PLACE.

PAPER-CUTTER.

SPECIFICATION forming part of Letters Patent No. 392,416, dated November 6, 1888.

Application filed February 13, 1888. Serial No. 263,798. (No model.)

To all whom it may concern:

Be it known that I, LEO EHRLICH, of the city of St. Louis, in the State of Missouri, have invented a certain new and useful Improvement in Paper-Cutters, of which the following is a full, clear, and exact description, reference being had to the accompanying drawings, forming part of this specification, and in which—

Figure I is a side elevation of my improved paper-cutter. Fig. II is an end view.

My invention relates to an improvement in devices for holding and cutting wrapping paper; and my invention consists in features of novelty hereinafter fully described, and pointed out in the claims.

Referring to the drawings, 1 represents a suitable base, to which are secured end pieces, 2. On the tops of these end pieces there are extensions 3, upon which the roller 4, holding 20 the paper 5, is supported and moves in a horizontal plane.

6 represents arms pivoted to the ends at 7. The lower faces of these arms are inclined, as shown in Fig. II, and they bear upon the gudgeons 8 of the roller 4. The action of the arms upon the roller is to force the latter outward on the extensions 3 as the paper is removed. This is caused by the weight of the arms and the inclines on their lower edges.

9 represents the knife, which is journaled to 30 the outer ends of the arms 6, and which rests upon the paper, as shown.

10 represents bars extending over the journals of the roller to keep them on the extensions 3, these arms being preferably formed in 35 one piece with the extensions, as shown in Fig. II.

I claim as my invention—

1. In a paper-cutter, the combination of the roller, a support for the roller, pivoted arms, 40 and a knife on the arms, said arms bearing upon the gudgeons or journals of the roller, and being inclined to cause the roller to move toward the knife as the paper is removed, substantially as set forth.

2. The combination, in a paper-cutter, of the base, ends secured to the base, extensions on the ends, roller having extended gudgeons or journals bearing on the extensions of the ends, arms pivoted to the ends, and knife secured to 50 the outer ends of the arms, said arms being inclined on their under edges and bearing upon the extended journals or gudgeons, substantially as and for the purpose set forth.

LEO EHRLICH.

In presence of—

EDWD. S. KNIGHT,
JOS. WAHLE.
